Patented Dec. 5, 1916.

UNITED STATES PATENT OFFICE.

OSCAR W. SANDHOLM, OF ROCKAWAY BEACH, NEW YORK.

WINDOW-JACK.

1,207,442.

Specification of Letters Patent.

Patented Dec. 5, 1916.

Application filed November 23, 1915. Serial No. 62,959.

To all whom it may concern:

Be it known that I, OSCAR W. SANDHOLM, a citizen of the United States, and a resident of Rockaway Beach, in the county of 5 Queens and State of New York, have invented a new and Improved Window-Jack, of which the following is a full, clear, and exact description.

This invention relates to seats and particularly to a window sill seat or jack, and has for an object the provision of an improved arrangement whereby the same may be applied and removed quickly and when applied be held against accidental removal.

15 Another object in view is to provide a seat or jack of the character described which may be placed on substantially any sized window and adjusted to properly clamp the same.

In the accompanying drawings: Figure 1 20 is a perspective view of a seat or jack embodying the invention; Fig. 2 is a transverse vertical section through part of the wall and window frame together with part of a seat or jack disclosing an embodiment of the invention, the section being substantially on the line 2—2 of Fig. 1; Fig. 3 is a front view of the structure shown in Fig. 1; Fig. 4 is a section through Fig. 2 on line 4—4; Fig. 5 is a detail fragmentary sectional view 25 through Fig. 2 on line 5—5; Fig. 6 is a detail fragmentary sectional view through Fig. 2 on line 6—6.

Referring to the accompanying drawing by numerals, 17 indicates a body which may 30 be of metal or other suitable material and which is provided with slots 18 and 19 accommodating the bolts 20 and 21, which bolts extend through the body and also through a sliding bar 22. Wing nuts 23 are 35 provided so as to clamp the bolts 20 and 21 in any desired adjusted position. Each of the bars 22 is provided with a hook 24 at one end, as shown more particularly in Figs. 1 and 2, for hooking over the stool 7 of the window. The bolts 20 and 21 are preferably 40 adapted to pass through small apertures in the respective bars 22, while a guiding and clamping bolt 25 passes through the body 17, a slot 26 in bar 22 and through a turnedover end 27 of each of the supporting runners 28. As shown in Figs. 4, 5 and 6, the bar 22 fits in an inclosing guide 29, which guide may be soldered or otherwise 45 rigidly secured to the body 17. In addition to runner 28 which rests upon the sub-sill 13

is an auxiliary runner 30 resting on the sill 16 so that there will be no appreciable weight directly on the bars 22.

By adjusting the bolts 20 and 21 the device may be adapted to windows of various 60 sizes and may be properly clamped in position by the hook ends 24 and the screw members 14. The bent-over portion 27 of runner 28 is held in place by bolt 25 and also, if desired, by being soldered to the guide 29, 65 while the auxiliary runner 30 may be held in place by solder if desired. However, the same is clamped in position together with the guide 29 by a clamping band 31.

By arranging a jack or seat of this character 70 an ample support is provided for a person when cleaning the outside of windows or when operating on the outside of windows for any other purpose, as for instance, painting or putting the parts of the 75 window sash.

What I claim is:

1. In a window cleaning seat of the character described, a body provided with a pair of slots therein, a support therefor having 80 a runner engaging the sill adjacent the window frame for supporting the outer part of the body, a pair of slideable bars arranged beneath said body and overlapping part of the window sill, a bolt extending through 85 each of said bars and through the slots of said body whereby the bars may be clamped at any desired position, and a hook member arranged on the free end of each of said bars, said hook members being adapted to be 90 hooked over the stool of the window, and an adjustable member arranged on said runner and acting against said runner and the window sill for holding said hook tightly 95 against said sill whereby the hooks will hold the entire seat in position.

2. In a window cleaning seat of the character described, a body provided with a pair of slots therein, a support therefor comprising 100 an inner comparatively low runner for supporting one edge of the body and an outer comparatively high runner engaging the sill adjacent the window frame for supporting the outer part of the body, a pair of slideable bars arranged beneath said body, a bolt extending through each of said bars and through the slots of said body, whereby 105 said bars may be clamped at any desired position, and a hook member arranged on the free end of each of said bars, said hook 110

members being adapted to be hooked over the stool of the window, and an adjusting member arranged on said outer runner, said adjustable means acting against said outer runner and the window sill for holding said hooks tightly against said sill.

In testimony whereof I have signed my

name to this specification in the presence of two subscribing witnesses.

OSCAR W. SANDHOLM.
